UNITED STATES PATENT OFFICE.

FRANK D. SHEPHERD, OF SALT LAKE CITY, UTAH.

PUPPET-VALVE FOR INTERNAL-COMBUSTION ENGINES.

1,252,501.

Specification of Letters Patent.

Patented Jan. 8, 1918.

Application filed May 21, 1917. Serial No. 169,945.

To all whom it may concern:

Be it known that I, FRANK D. SHEPHERD, a citizen of the United States, and resident of Salt Lake City, Utah, have invented a certain new and useful Improvement in Puppet-Valves for Internal-Combustion Engines, and do hereby declare that the following is a full, clear, and exact description thereof.

10 My invention relates to puppet valves and especially those adapted for use with internal combustion engines, and my object generally stated, is to provide a valve construction which will increase the power of the engine, or to put it differently, will secure economy of use of fuel; which will efficiently and certainly perform its functions of closing and opening, so that when closed upon its seat it can be depended upon to cut off completely the flow of gas, and when open will allow free and ample passage; will be simple of construction, hence contribute to economy of manufacture as well as eliminating danger of becoming disordered; and will be readily 20 and easily accessible for removal and replacement of the parts, whose removal and replacement may be desirable, and for the attainment of this object and others which will be understood by those skilled in the art 25 when the characteristics of the valve embodying my invention are understood from the accompanying drawings and description, my invention consists in the valve mechanism constructed substantially as herein- 30 after specified and claimed.

In the accompanying drawings which illustrate several forms, or embodiments of my invention—

Figure 1 is a vertical section through an internal combustion engine having a valve embodying my invention;

Fig. 2 is a similar view, but showing only the valve mechanism and immediately adjacent parts, of another embodiment of my invention;

Fig. 2¹ is a detail view, in side elevation with parts in section, showing an integral construction of valve stem and spring-engaging disk;

50 Figs. 3 and 4 are detail views, in section, showing the lower portion of each of two forms of spring container and guide in which my invention may be embodied, differing from the similar device shown in other 55 figures;

Fig. 5 is a detailed view, in side elevation, showing a different form of valve and valve stem arrangement, embodying my invention;

Figs. 6, 7, and 8 are detail views showing various forms of cover plates for the spring container;

Fig. 9 is a detail view, in side elevation, showing still another form of valve and valve stem embodying my invention;

Fig. 10 is a detail view, with parts in section, showing a means for rotatably connecting a loose valve stem and valve head for grinding the latter on its seat;

Fig. 11 is a top plan view of the valve head alone in the arrangement shown in Fig. 10;

Fig. 12 is an end view of the lower end of the valve stem alone in said arrangement;

Fig. 13 is a detail view, in side elevation, of a tool enabling the valve head of the loose valve head and valve stem construction, as shown in Figs. 2 and 10, to be ground on its seat.

Giving a detail description of the construction shown in Fig. 1 of the drawing, the engine cylinder 10 shown is of the type having the head 11 cast integral therewith, and connected with said head there are as many puppet valves, as, in the judgment of the designer, it is proper, or desirable to employ, but for the purpose of disclosing my invention to those skilled in the art it is not necessary to show and describe more than one valve mechanism, which thus is to be taken as representative, or typical for both the intake and the exhaust, and for as many as it may be desirable, or expedient to employ. My invention, as will be evident, has to do with the valve construction and not with the number employed (although its construction is such as to render unnecessary multiplication of the number); nor is my invention concerned with the particular type, or construction of the engine, or the mechanism for lifting the valve from its seat.

In the engine head eccentric to the cylinder, I provide an opening 12 which extends from the outer end of the head into the port 13, which is controlled by the valve mechanism, for which purpose, directly in line with said opening 12 and on the opposite side of the port it has a beveled seat 14 for the puppet valve 15 whose face, or rim is correspondingly beveled so that it closely, and in a gas tight manner, fits its seat. Se-

cured in said hole 12 is one end of a cylindrical shell 16. The portion of the shell within the hole may have a slip fit therein (as shown in Figs. 1 and 2), in which case, 5 the shell is held in place by screws or bolts 17 that pass through holes in lugs or flanges 16^a and into tapped holes in the cylinder head. Or, as illustrated in Figs. 3 and 4, the portion of the shell in the hole in the cylinder head may be externally threaded so as to screw into thread cut on the wall of the hole. In any case, a gas tight joint is formed by a 10 gasket between abutting surfaces of shell and cylinder head. The outer end of the shell 16 is closed by a cap plate 18 which is bolted to the outer end of the shell by bolts 19, passing into threaded holes in lugs or flanges on the shell, a gas tight joint being 15 assured by the provision of a gasket between the abutting surfaces of the cap plate and the shell 16. The cap plate and the flanges or lugs on the shell may have any desirable contour, such for example, as the oval, triangular, or square shapes shown in Figs. 6, 20 7, and 8.

The inner end of the shell or the end contiguous to the port 13 is closed save for a central hole 20 through which passes, with a sliding fit, a stem 21 on the valve, said stem 30 reaching into the chamber in said shell and having mounted upon it a disk, or head 22 of substantially the diameter of the chamber in the shell and upon which head bears the inner end of an expansible coil spring 23, 35 which by pressure on the valve transmitted through said head and stem yieldingly holds the valve to its seat from which it is lifted by the usual lifter cam 24 acting through a stem 25 on the opposite side of the valve 40 from the stem 21. It will be observed that the spring 23 is concentric with the valve axis, and hence, exerts a pressure on the valve which is balanced, that is to say, it is accompanied by no sidewise, or tilting action, 45 and hence, no tendency to wear of the stem and guide on one side with a consequent tilting, or cocking of the valve on its seat enough to cause leakage. Another evil resulting from such unequal wear, is the sucking in of air which spoils the mixture of gas 50 from the carburetor and thus the power of the engine is impaired. A serious objection to leakage of gas past the valve is erosion, or cutting by the gas that takes place.

55 The spring bearing-head 22 may be integral with the valve stem as shown in Fig. 2^a or formed separate therefrom, Figs. 1 and 2, in which case, it has a central hole that fits the reduced end of the valve stem and is 60 seated upon a shoulder 26 formed by the reduction of the end of the valve stem and whether the construction be integral or separate, the valve stem projects slightly beyond the head 22 to give access to a suitable tool 65 for grinding the valve on its seat, the valve

stem having the proper formation for engagement by said tool. From end to end the head 22 is perforated, as by several holes 27, to allow the free passage of air, and thereby prevent such suction between the inner side 70 of the head and the adjacent stationary surface as would hinder, or obstruct, perfectly free movement of the head and of the valve when the latter is lifted from its seat, and to prevent the existence of an air cushion 75 that would obstruct, or hinder the seating movement of the valve. There is no communication between the interior of the shell and the outside air.

When the spring bearing head 22 is made 80 separate from the valve stem it can be either detachably or permanently connected to the stem 21 and in any desired way. It may simply slip on the reduced end of the stem 21 and the stem end riveted or headed down; 85 or it may be screwed on to the stem and the projecting end of the stem upset; or it may be welded to the stem. The pressure of the spring on said head 22, even if the connection be a loose one, obviously serves to hold 90 the head on the stem.

The stem 21 may be integral with the valve head, as shown in Figs. 1 and 5 or it may be separate therefrom, as shown in Figs. 2, 2^a, 10 and 11, and the stem 25 may 95 be integral with the valve, as shown in Figs. 2 and 5, or separate therefrom as shown in Figs. 1 and 9. The valve head may have in its under seat a semispherical cavity or socket 28, and the contiguous end of the stem 100 provided with a ball-like or rounded end 29, so that a ball and socket joint is provided, which renders the construction a very flexible one that compensates for any inequality in alinement of parts and assures the tight 105 seating of the valve.

The valve head is given ample body to enable it to stand tremendous pressure and temperature without warping or bending out of shape, by giving it on either or both 110 sides a substantially conical form, so that it gradually thickens in diameter from the stem outward. As shown in Fig. 1, the thickened portion is on the side toward the stem 21, while in Figs. 2 and 5, it is on the 115 opposite side. When on the side shown in Fig. 1, to accommodate this thickened portion of the head when the valve lifts from its seat, the end of the shell 16 toward the valve is provided with a correspondingly shaped 120 cavity 31 which extends inward from the plane of the outer wall of the port 13. Thus ample space for the movement of the valve is provided without unduly increasing the depth of the port 13. As clearly shown in 125 Fig. 1, the diameter of the smaller end of the cavity 31 is substantially greater than the diameter of the stem and the hole in the shell through which the stem passes, so that a shoulder 32 is provided that surrounds the 130

stem at the inner end of the cavity, which performs the useful function of scraping from the valve stem any deposits of carbon or other matters upon the valve stem and thus the danger of such deposits wedging or packing in the concavity, and causing the valve to stick is avoided. This consideration is of special importance in view of the use of low gravity gasoline and fuel oil whose combustion results in a good deal of carbon and gummy matters.

As shown in Fig. 1, I employ a liner for the interior of the shell 16, and for the opening in the inner end of the shell through which the valve stem 21 is guided. The liner for both may consist of a single shell 33 with comparatively thin walls. Said liner is removable so that when wear from the action of the spring and the stem results, it is not necessary to discard the entire shell, but merely to remove the worn liner and replace it. Said liner may be made of cheaper metal than the shell, or vice versa, so as to reduce the cost of manufacture and it may be made of the alloy known as frictionless or self-lubricating metal and thus make unnecessary any special lubricant. The liner can be secured to the shell by being pressed into place or in any other desired way. If desired, as shown in Figs. 2 and 4, the liner may be used only about the stem 21, and as illustrated in Fig. 3, a construction may be employed in which it is omitted altogether.

The valve head may be beveled on the side opposite the seating side as well as on the latter, as thereby the gases will pass more freely around the valve head, but I do not limit myself to beveling both sides or either side.

40 As shown in Fig. 9, the lifting stem when made separate from the valve head may be provided with an enlargement 34 at its upper end which bears against the lower end of a substantially conical enlargement or projection on the under side of the valve head.

45 A disk 35 of insulating material may be placed at the bottom of the spring container or shell 16 to prevent the transmission of objectionable temperature to the interior of the spring container with consequent injury to the temper of the spring, but I do not limit myself to the employment of such insulator. When used, it may be of any suitable material that is a non-conductor of heat.

55 To reduce the unoccupied space or volume in the shell 16 to a minimum and thus preclude the presence in said shell of more than a negligible quantity of gas should leakage into the shell occur, I place within the outer end of the coil spring a filling piece of as large a diameter and of as great length as possible without interfering with the play of the spring and the movements of the valve. This idea may be carried out in various forms, such for example, as those shown in

my application for Patent, No. 147,396, filed Feb. 8, 1917. I illustrate in this application but one construction embodying such idea, it being shown in Fig. 1. Said filling piece is in the form of a cylindrical block 36, situated within the outer end portion of the coil spring and having on its outer end, a flange or head 37 that affords a bearing for the outer end of the spring. Said head 37 is engaged on its outer face by an adjusting screw 38 which passes through the cover plate or cap 18, which thus enables the tension of the spring to be readily adjusted. The lock nut 39 is applied to the screw 38 to hold it at the desired adjustment.

80 The spring container or shell 16 may be made smooth on its outer side as shown in Figs. 1, 3, and 4, or, as shown in Fig. 2, it may be provided with ribs or fins for air-cooling purposes, as illustrated in my before 85 mentioned application. Matters of this sort will depend upon the kind and requirements of the engine and the valve.

I have shown various forms, or embodiments of my invention, in order that it may 90 be understood that I realize that such invention may exist in different forms. It, of course, can have embodiments other than those selected by way of example, and, hence, it is to be understood that I regard myself 95 as entitled to its embodiments in still other forms than those shown in the drawings.

When the upper valve stem is made separate from the valve head as shown in Figs. 2, 2^a, 11 and 12 any one of several ways may 100 be pursued for applying power to the head 15 to rotate the same for grinding it on its seat; for example, as shown in Figs. 10, 11, and 12, a square or other angular shaped coupling pin 40 may enter a correspondingly 105 shaped socket 41 in the top of the valve head, and a correspondingly shaped socket 42 in the lower end of the valve stem 21; or as shown in Fig. 13, a tool 43 may be employed having at its lower end a squared or 110 other angular shaped projection 44 adapted to fit the socket 41 in the upper side of the valve head 15, and having at its upper end an angular shank 45 adapted to be engaged with the socket of a brace.

115 Having thus described my invention, what I claim is:—

1. The combination of an engine cylinder having a valve-controlled passage, with a valve seat, a puppet valve, a shell or container, a spring in said shell, a valve stem passing through an opening into the container and acted upon by said spring, and a removable liner for said container.

2. The combination of an engine cylinder having a valve controlled passage, with a valve seat, a puppet valve, a shell or container, a spring in said shell, a valve stem passing through an opening into the container and acted upon by said spring, and a

removable liner for said container with portions that inclose the spring and the stem.

3. The combination of an engine cylinder having a valve-controlled passage with a valve seat, a puppet valve, a shell or container, a spring in said shell acting to hold the valve yieldingly to its seat, a stem extending from the valve into said shell, the valve having a tapering thickened portion 10 reaching to the stem, and a surface opposite the valve seat that has a cavity to receive said thickened portion of the valve, said cavity being substantially larger in diameter at its inner end than the stem, to form 15 a space thereat around the stem.

4. The combination of an engine cylinder having a valve-controlled passage, with a valve seat, a puppet valve, a shell or container, a spring in said shell, a filling piece 20 in said spring for a portion of its length and, having a spring engaging shoulder, and a

spring tension-adjusting device, engaging said filling piece.

5. The combination of an engine cylinder, having a valve controlled passage with a valve seat, a puppet valve, a lifting stem made separate from the valve, and a ball and socket bearing between the valve and said stem.

6. The combination of an engine cylinder 30 having a valve-controlled passage, with a valve seat, a puppet valve, a shell or container, a spring in said shell, a valve stem passing through an opening into the container and acted upon by said spring, and a removable liner for said container with portions that inclose the spring and the stem, said liner and said shell being of different material.

In testimony that I claim the foregoing I 40 have hereunto set my hand.

FRANK D. SHEPHERD.
